UNITED STATES PATENT OFFICE.

ERNST LAUSCHKE, OF CHICAGO, ILLINOIS, ASSIGNOR TO ARTHUR M. AND ALSON E. BARNHART, BOTH OF SAME PLACE.

DESIGN FOR TYPE.

SPECIFICATION forming part of Design No. 16,553, dated March 2, 1886.

Application filed January 15, 1886. Serial No. 188,692. Term of patent 14 years.

To all whom it may concern:

Be it known that I, ERNST LAUSCHKE, a subject of the Emperor of Germany, residing in the city of Chicago, county of Cook, and 5 State of Illinois, have invented and produced a new and original Design for a Font of Printing-Types, of which the following is a specification, reference being had to the accompanying typographical illustration, forming a part 10 hereof.

The general character of the design is grotesque, of medium weight; and it consists of capitals, points, character &, and lower-case. The special features are the curved lines, as 15 shown in capitals B D J K L O P Q R, lower-case b d h m n o p q u y, the disconnected center curved lines in capitals B K P R, the mitered vertical inclined and curved lines, and the wholly-severed vertical lines from any 20 other lines of the letters, as shown in lowercase b d h m n p q r y z. Capitals C G and lower-case a c f j r s t y have curved hair lines ending with a heavy dot. Some of the inclined vertical and curved lines of the letters extend below the general line of the other letters of the design, as shown in capitals A F M N P R and lower-case f h m n.

I claim—

The design for a font of printing-types of grotesque character, the heavy curved lines, 30 the severed vertical mitered strokes, the disconnected curved lines, and the fine curved lines with dot termination, as described, and shown in the accompanying typographical illustration.

ERNST LAUSCHKE.
